21-NITROGEN SUBSTITUTED STEROIDS OF THE PREGNANE SERIES AND METHODS OF PREPARING THE SAME

Michael Marx, Leonia, N.J., and Leland L. Smith, New City, N.Y., assignors to American Cyanamid Company, New York, N.Y., a corporation of Maine
No Drawing. Filed June 7, 1960, Ser. No. 35,388
13 Claims. (Cl. 260—239.55)

This invention relates to new steroid compounds. More particularly, it relates to 21-nitrogen derivatives of steroids of the pregnane series and to methods of preparing the same.

In the past, many steroids of the pregnane series having various substituents in the 21-position have been described such as hydroxy, alkanoyloxy, oxygen, halogen, etc. However, no 21-nitrogen substituted steroids of the pregnane series of our invention have been described.

We have found that compounds having the following structural formula are physiologically active steroids.

wherein C_2-C_1 and C_6-C_7 are divalent radicals selected from the group consisting of

and

radicals, X is selected from the group consisting of hydrogen, chlorine, and fluorine atoms, Z is a divalent radical selected from the group consisting of

radicals, R^1 is a member of the group consisting of hydrogen and lower alkyl radicals, R^2 is a member of the group consisting of hydrogen, halogen, and lower alkyl radicals, R^3 is a member of the group consisting of hydrogen, hydroxyl, fluorine, lower alkyl and lower alkanoyloxy radicals, at least one of the radicals R^1 , R^2 and R^3 being other than hydrogen, R^4 is a member of the group consisting of hydrogen, hydroxyl, and lower alkanoyloxy radicals; and R^5 and R^6 when taken together form lower alkylidenedioxy and (1-alkoxy)-lower alkylidenedioxy radicals, R^5 is a member of the group consisting of amino and lower alkanoylamino radicals, R^6 is hydrogen and R^5 and R^6 taken together is the radical

2

=NOH and pharmaceutically acceptable acid addition salts thereof.

The present invention includes pharmaceutical compositions comprising compounds as described above with a pharmaceutically acceptable carrier. The invention also includes acid addition salts of the compounds described above, such salts being for example the hydrochloride, hydrobromide, hydroiodide, nitrate, sulfate, phosphate, acetate, citrate, tartrate, fumarate, gluconate and the like.

The compounds of the present invention can be prepared by the process outlined as follows.

wherein R^3 is a member of the group consisting of hydrogen, hydroxyl, fluorine, lower alkyl and alkanoyloxy radicals. R^4 is a member of the group consisting of hydrogen, hydroxyl and alkanoyloxy radicals and R^3 plus R^4 when taken together form lower alkylidenedioxy and (1-alkoxy) lower alkylidenedioxy radicals, and R^5 is a member of the group consisting of amino and lower alkanoylamino radicals.

The first step of the process illustrated above as (A) to (B) can be carried out as described in United States Patent 2,773,078 wherein a 21-hydroxy steroid of the pregnane series is treated in an alcohol with a copper salt, for example, glacial acetic acid. The second step, (B) to (C), can be carried out by the selective formation of the 21-oxime using hydroxylamine or a salt thereof. The reactants are generally mixed together at room temperature or below and the reaction mixture is heated to a temperature within the range of 60° C. to 90° C. for a period ranging from 1 hour to about 18 hours. The desired product can be obtained from the reaction mixture by methods well known and described in the examples hereinafter.

The reaction, (C) to (D), which is the selective reduction of the 21-oxime to the 21-amine, is generally accompanied by the formation of a pharmaceutically acceptable acid addition salt and is performed by employing metallic zinc and acetic acid under mild conditions. In this reaction a temperature within the range of from 0° to about 50° C. and preferably from 25° C. to 35° C. is used. The reaction is completed usually within a period of from about 10 minutes to 120 minutes. In carrying out the reaction preferably an alkali metal acetate and a catalyst such as a mercury salt is also present. Other amino derivatives such as 21-alkanoylamino compounds can be prepared essentially in the same manner wherein the 21-oxime is selectively treated with an acylating agent such as an alkanoyl anhydride in addition to the

conditions for the preparation of the 21-amino compound.

When the reaction is complete the desired product in the case of the 21-oxime can be obtained by evaporation of the organic solvent and amine reagent under reduced pressure. The product is further purified by crystallization as shown hereinafter in the examples. When purifying the 21-amine after the reaction is complete it can be separated from the insolubles by filtration and neutralized with an alkali metal bicarbonate. The product is taken up in a water immiscible organic solvent such as methylene chloride, ether, benzene, etc. After the organic layer is separated it is washed with the alkaline aqueous phase and evaporated to dryness under reduced pressure to produce the desired compound which can be further purified by methods well known in the art.

The compounds of the present invention are active glucocorticoids and mineralocorticoids. The glucocorticoid activity makes the compounds useful as antiarthritics and in the treatment of burns, skin disorders and similar conditions requiring topical application. The mineralocorticoid activity makes the compounds useful in the treatment of edema and other conditions manifested by water in the tissues. The acid salts of the present compounds are of particular value with regard to water solubility. Compounds such as 21-amino-11 β ,17 α -dihydroxy-6 α -methyl-1,4-pregnadiene-3,20-dione hydrochloride are water soluble anti-inflammatory agents useful in the treatment of rheumatoid arthritis.

The steroids of the present invention can be dispensed in the usual pharmaceutical forms such as tablets, capsules, liquids, suspensions or similar dosage forms. They may be in dosage unit form for single daily therapeutic doses or in small units for multiple doses or in larger units for division into single doses. Obviously, in addition to the therapeutic products, there may be present excipients, binders, fillers and other therapeutically inert ingredients necessary in the compounding of pharmaceutical preparations.

The following examples illustrate the preparation of representative 21-nitrogen substituted steroids of the pregnane series.

EXAMPLE 1

Process for the production of 9 α -fluoro-11 β ,17 α -dihydroxy-3,20-dioxo-4-pregn-21-al 21-oxime

A heated solution of 27 grams of cupric acetate in 1400 milliliters of methanol is added to a heated solution of 20 grams of 9 α -fluoro-11 β ,17 α ,21-trihydroxy-4-pregnene-3,20-dione in 1000 milliliters of methanol containing 20 milliliters of glacial acetic acid and the resulting mixture refluxed for about 30 minutes. Approximately 800 milliliters of water is added and heating continued for an additional 30 minutes. The reaction mixture is then filtered to remove insoluble cuprous oxide, the resulting filtrate diluted with about 400 milliliters of water, and the resulting solution evaporated under reduced pressure to about 1000 milliliters. The crystal slurry thus produced is allowed to stand for about 16 hours at 4° C., after which time the formed crystals are collected by filtration. The yield is 13.1 grams of 9 α -fluoro-11 β ,17 α -dihydroxy-3,20-dioxo-4-pregn-21-al (hydrate) λ_{max} 239 m μ (ϵ 17,150); infrared bands (in KBr) at 2.88 μ , 3.40 μ , 5.83 μ , 6.10 μ , 9.65 μ , etc.

A solution of 1.0 gram of 9 α -fluoro-11 β ,17 α -dihydroxy-3,20-dioxo-4-pregn-21-al and 200 milligrams of hydroxylamine hydrochloride in a mixture of 10 milliliters of pyridine and 10 milliliters of ethanol is heated for about 90 minutes on the steam bath. The reaction mixture is evaporated under reduced pressure to about 5 milliliters, and water is added in a quantity sufficient to produce a gummy precipitate. The solvent mixture is decanted and the residue washed several more times by decantation with water. The washed residue is crystallized from aqueous methanol and the crystals collected

by filtration, and dried. The yield is 625 milligrams of 9 α -fluoro-11 β ,17 α -dihydroxy-3,20-dioxo-4-pregn-21-al 21-oxime melting point 210°-211° C.; λ_{max} 235 m μ (ϵ 25,600); infrared bands (in KBr) at 2.85 μ , 3.05 μ , 3.40 μ , 5.88 μ , 6.16 μ , 6.98 μ , 9.60 μ , 11.25 μ , etc.

EXAMPLE 2

Process for the production of 21-acetylamino-9 α -fluoro-11 β ,17 α -dihydroxy-4-pregnene-3,20-dione

10 To a stirred solution of 100 milligrams of 9 α -fluoro-11 β ,17 α -dihydroxy-3,20-dioxo-4-pregn-21-al 21-oxime, 20 milligrams of sodium acetate, and 5 milligrams of mercuric chloride in 10 milliliters of glacial acetic acid there is added, in small portions over 30 minutes, 300 milligrams of zinc dust. After stirring for an additional 90 minutes, the reaction mixture is diluted with about 150 milliliters of ether and the insoluble inorganic materials filtered off. To the filtrate is added about 1.5 equivalents, based on steroid, of 70 percent aqueous perchloric acid. The small quantity of flocculent precipitate which forms is removed by filtration. The filtrate is allowed to stand for about 18 hours. The crystals which form are collected by filtration and air dried. The yield is 60 milligrams of 21-amino-9 α -fluoro-11 β ,17 α -dihydroxy-4-pregnene-3,20-dione perchlorate melting point 211°-213° C.

20 Acetylation of the above product with acetic anhydride and pyridine at room temperature produces the desired 21-acetylamino compound melting point 263°-264° C.

25 To a stirred solution of 100 milligrams of 9 α -fluoro-11 β ,17 α -dihydroxy-3,20-dioxo-4-pregn-21-al 21-oxime, 20 milligrams of sodium acetate, and 5 milligrams of mercuric chloride in a mixture of 6 milliliters of glacial acetic acid and 5 milliliters of acetic anhydride there is added, in small portions over a 30 minute period, 300 milligrams of zinc dust. After stirring for an additional 90 minutes, the reaction mixture is filtered to remove unreacted zinc and insoluble inorganic salts. The filtrate is concentrated to near dryness under reduced pressure and the concentrate thus obtained is diluted with water and extracted with methylene chloride. The methylene chloride extract is washed with saturated aqueous sodium bicarbonate, dried over anhydrous magnesium sulfate, and concentrated to dryness under reduced pressure to give a crystalline residue from which is obtained, after two recrystallizations from acetone-petroleum ether, 60 milligrams of 21-acetylamino-9 α -fluoro-11 β ,17 α -dihydroxy-4-pregnene-3,20-dione. λ_{max} 237 μ (ϵ 16,200); infrared bands (in KBr) at 3.00 μ , 3.40 μ , 5.80 μ , 6.02 μ , 6.54 μ , 7.03 μ , 9.62 μ , 11.27 μ , etc.

EXAMPLE 3

Process for the production of 9 α -fluoro-11 β -hydroxy-16 α ,17 α -isopropylidenedioxy-3,20-dioxo-1,4-pregnadien-21-al 21-oxime

55 A solution of 4.5 grams of cupric acetate in 300 milliliters of hot methanol is added to a solution of 3.0 grams of 9 α -fluoro-11 β ,21-dihydroxy-16 α ,17 α -isopropylidenedioxy-1,4-pregnadiene-3,20-dione in 180 milliliters of hot methanol containing 3 milliliters of glacial acetic acid, and the resulting mixture refluxed for about 30 minutes. Approximately 100 milliliters of water are added and refluxing continued for an additional 30 minutes. The precipitated cuprous oxide is removed by filtration, the filtrate diluted with 150 milliliters of water, and the resulting solution concentrated to about 500 milliliters under reduced pressure. The crystal slurry thus produced is allowed to stand for about 16 hours at about 4° C.; then the crystals are removed by filtration and dried to give 2.71 grams of 9 α -fluoro-11 β -hydroxy-16 α ,17 α -isopropylidenedioxy-3,20-dioxo-1,4-pregnadien-21-al (hydrate) melting point 273°-275° C.

60 A solution of 2.0 grams of 9 α -fluoro-11 β -hydroxy-16 α ,17 α -isopropylidenedioxy-3,20-dioxo-1,4-pregnadien-

21-al and 325 milligrams of hydroxylamine hydrochloride in a mixture of 20 milliliters of pyridine and 20 milliliters of ethanol is heated for about 90 minutes on the steam bath. The reaction mixture is evaporated to about 10 milliliters under reduced pressure and water is added to the concentrate to precipitate the crude product. After washing several times by decantation with water, the residue is crystallized from aqueous methanol. The crystals are collected by filtration and dried to give 1.44 grams of 9α -fluoro- 11β -hydroxy- $16\alpha,17\alpha$ -isopropylidenedioxy-3,20-dioxo-1,4-pregnadien-21-al 21-oxime having a melting point of 258-260° C. infrared bands (in KBr) at 2.88μ , 3.05μ , 3.40μ , 3.70μ , 5.88μ , 6.05μ , 6.28μ , 6.90μ , 9.48μ , etc.

EXAMPLE 4

Preparation of 21-amino- 9α -fluoro- 11β -hydroxy- $16\alpha,17\alpha$ -isopropylidenedioxy-1,4-pregnadiene-3,20-dione

A solution of 200 mg. of 9α -fluoro- 11β -hydroxy- $16\alpha,17\alpha$ -isopropylidenedioxy-3,20-dioxo-1,4-pregnadien-21-al 21-oxime, as prepared in Example 3, 40 mg. of sodium acetate and 10 mg. of mercuric chloride in 15 ml. of glacial acetic acid is treated with 600 mg. of zinc dust added over a period of 15 minutes, at room temperature. The reaction mixture is stirred an additional 15 minutes, then filtered from insolubles. The solids are washed with methylene chloride, and the washings and initial filtrate are combined and further diluted with water and the aqueous phase is neutralized with sodium bicarbonate. The methylene chloride layer is removed, the aqueous phase re-extracted twice with additional methylene chloride, and the combined extracts are washed with saturated aqueous sodium bicarbonate solution. The extracts are dried and evaporated to dryness under reduced pressure giving the product, 21-amino- 9α -fluoro- 11β -hydroxy- $16\alpha,17\alpha$ -isopropylidenedioxy-1,4-pregnadiene-3,20-dione. The hydrochloride salt has the following characteristics. λ_{max} 239 μ .

($E_{1\text{cm}}^{1\%}$ 306)

Infrared absorption at (KBr) 2.92μ , 3.40μ , 3.85μ , 5.79μ , 6.01μ , 6.16μ , 6.23μ , 9.40μ , 11.20μ , etc.

EXAMPLE 5

Preparation of 21-acetylamino- 9α -fluoro- 11β -hydroxy- $16\alpha,17\alpha$ -isopropylidenedioxy-1,4-pregnadiene-3,20-dione

A solution of 70 mg. of 21-amino- 9α -fluoro- 11β -hydroxy- $16\alpha,17\alpha$ -isopropylidenedioxy-1,4-pregnadiene-3,20-dione, prepared as in Example 4, in 5 ml. of pyridine and 1 ml. of acetic anhydride is allowed to stand for 18 hours at room temperature. Dilution of the reaction solution with methanol and removal of the solvents under reduced pressure gives the product, 21-acetylamino- 9α -fluoro- 11β -hydroxy- $16\alpha,17\alpha$ -isopropylidenedioxy-1,4-pregnadiene-3,20-dione.

EXAMPLE 6

Preparation of 21-acetylamino- 9α -fluoro- 11β -hydroxy- $16\alpha,17\alpha$ -isopropylidenedioxy-1,4-pregnadiene-3,20-dione

A solution of 1.5 g. of cupric acetate monohydrate in 100 ml. of hot methanol is added to a solution of 1.0 g. of 9α -fluoro- $11\beta,17\alpha,21$ -trihydroxy- 16α -methyl-1,4-pregnadiene-3,20-dione in 60 ml. of hot methanol containing 1 ml. of glacial acetic acid, and the mixture heated at reflux for 30 minutes. Refluxing is continued for 30 minutes after addition of 50 ml. of water. The precipitated copper salts are removed by filtration, 50 ml. of water is added to the filtrate, and the resulting solution evaporated under reduced pressure until crystallization commenced. The crystallization mixture is aged overnight in the cold, and the crystals are collected by filtration to give 455 mg. of 9α -fluoro- $11\beta,17\alpha$ -dihydroxy- 16α -methyl-3,20-dioxo-1,4-pregnadien-21-al which as the hydrate melted at 127-130° C.

A solution of 400 mg. of 9α -fluoro- $11\beta,17\alpha$ -dihydroxy-

5 16α -methyl-3,20-dioxo-1,4-pregnadien-21-al (prepared as in Example 9) and 75 mg. of hydroxylamine hydrochloride in a mixture of 5 ml. of pyridine and 5 ml. of ethanol is heated for 2 hours on the steam bath. The reaction mixture is evaporated to near dryness under reduced pressure, and sufficient water is added to produce a gummy precipitate. The precipitate is washed several times by decantation with water, and finally crystallizes from aqueous methanol to give 280 mg. of 9α -fluoro- $11\beta,17\alpha$ -dihydroxy- 16α -methyl-3,20-dioxo-1,4-pregnadien-21-al 21-oxime.

EXAMPLE 7

Preparation of 21-amino- 9α -fluoro- $11\beta,17\alpha$ -dihydroxy- 16α -methyl-1,4-pregnadiene-3,20-dione hydrobromide

15 A stirred solution of 200 mg. of 9α -fluoro- $11\beta,17\alpha$ -dihydroxy- 16α -methyl-3,20-dioxo-1,4-pregnadien-21-al 21-oxime, as prepared in Example 6 in 20 ml. of propionic acid is treated with 500 mg. of zinc dust added over 30 minutes at room temperature. Stirring is continued for 30 more minutes, the solids removed by filtration, and the filtrate concentrated to near dryness under reduced pressure. Addition of ethyl acetate produces a crystalline precipitate of zinc propionate, which is filtered off. The 20 filtrates are diluted with anhydrous ether, one and one-half equivalents of hydrobromic acid are added, and the mixture aged 16 hours at room temperature whereupon the precipitated 21-amino- 9α -fluoro- $11\beta,17\alpha$ -dihydroxy- 16α -methyl-1,4-pregnadiene-3,20-dione hydrobromide is 25 collected by filtration.

EXAMPLE 8

Preparation of 17 α -hydroxy-3,11,20-trioxo-4-pregnen-21-al 21-oxime

35 A solution of 5 grams of cortisone 21-aldehyde (17α -hydroxy-3,11,20-trioxo-4-pregnen-21-al) and 1.2 grams of hydroxylamine sulfate in 100 ml. of 50% ethanolic pyridine is heated for one hour on a steam bath. The reaction mixture is then reduced in volume under diminished pressure and water is added to precipitate the product oxime. The oxime is decanted from the solvents, washed with water, and crystallized from hot aqueous methanol. The crystalline cortisone aldehyde 21-oxime is 40 filtered, washed with small portions of cold aqueous methanol and dried.

EXAMPLE 9

Preparation of 11 $\beta,17\alpha$ -dihydroxy- 6α -methyl-3,20-dioxo-1,4-pregnadien-21-al 21-oxime

50 A heated solution of 27 g. of cupric acetate in 1400 ml. of methanol is added to a heated solution of 20 g. of $11\beta,17\alpha,21$ -trihydroxy- 6α -methyl-1,4-pregnadiene-3,20-dione in one liter of methanol which contains 20 ml. of glacial acetic acid. The resulting mixture is refluxed on 55 a steam bath for a half an hour, at which time 800 ml. of water is added and the heating continued for an additional half an hour. The reaction mixture is filtered to remove insoluble inorganic salts and the filtrate is diluted with 500 ml. of water. The solution obtained is evaporated under reduced pressure to incipient crystallization and the suspension allowed to stand in an ice bath until crystallization is complete. The desired $11\beta,17\alpha$ -dihydroxy- 6α -methyl-3,20-dioxo-1,4-pregnadien-21-al is 60 filtered, washed with cold water and dried. The aldehyde did not reduce alkaline tetrazolium salts.

A solution of 10 g. of $11\beta,17\alpha$ -dihydroxy- 6α -methyl-3,20-dioxo-1,4-pregnadien-21-al as prepared in Example 9 and of 2 g. of hydroxylamine hydrochloride in 200 ml. of 50% ethanolic pyridine is heated for two hours on a 65 steam bath. The reaction mixture is evaporated under reduced pressure and water is added. The gummy solids produced are separated and washed with water. Crystallization of the 21-mono-oxime is accomplished from aqueous methanol, and the crystals are filtered, washed with aqueous methanol and dried. The yield is 5 grams.

EXAMPLE 10

Preparation of 21-amino-11 β ,17 α -dihydroxy-6 α -methyl-1,4-pregnadiene-3,20-dione hydrochloride

A solution of 200 mg. of 11 β ,17 α -dihydroxy-6 α -methyl-3,20-dioxo-1,4-pregnadien-21-al 21-oxime, 40 mg. of sodium acetate, and 10 mg. of mercuric chloride in 20 ml. of glacial acetic acid is prepared. To this solution is added small portions of zinc dust so that 600 mg. of zinc dust is added over 30 minutes. The suspension is well shaken during this time, and is stirred for 90 minutes after zinc addition. The reaction mixture is diluted with diethyl ether and insoluble inorganic materials are filtered. The ether solution is evaporated to dryness and the residue dried and redissolved in a mixture of absolute ether and ethyl acetate. A stream of dry hydrogen chloride gas is passed through the solution until precipitation of the amine hydrochloride salt is complete, at which time the crystalline salt is filtered off and dried under reduced pressure.

EXAMPLE 11

Preparation of steroidal 21-aldehydes

Using the procedures of Examples 1, 3, 5 etc. for the oxidation of the 21-hydroxy-20-ketosteroids to the 20-keto-21-aldehydes, the following 21-hydroxy-20-ketosteroids are oxidized and the corresponding 20-ketone-21-aldehyde is recovered:

6 α -fluoro-11 β ,17 α -21-trihydroxy-4-pregnene-3,20-dione;
 6 α -chloro-11 β ,17 α ,21-trihydroxy-4-pregnene-3,20-dione;
 6 α -fluoro-17 α ,21-dihydroxy-4-pregnene-3,11,20-trione;
 11 β ,17 α ,21-trihydroxy-2 α -methyl-4-pregnene-3,20-dione;
 17 α ,21-dihydroxy-2 α -methyl-4-pregnene-3,11,20-trione;
 17 α ,21-dihydroxy-2-methyl-1,4-pregnadiene-3,11,20-trione;
 11 β ,17 α ,21-trihydroxy-1,4-pregnadiene-3,20-dione;
 17 α ,21-dihydroxy-1,4-pregnadiene-3,11,20-trione;
 11 β ,17 α ,21-trihydroxy-4-pregnene-3,20-dione;
 11 β ,17 α ,21-trihydroxy-16 α -methyl-4-pregnene-3,20-dione;
 11 β ,17 α ,21-trihydroxy-16 α -methyl-1,4-pregnadiene-3,20-dione;
 16 α -fluoro-11 β ,17 α ,21-trihydroxy-4-pregnene-3,20-dione;
 16 α -fluoro-11 β ,21-dihydroxy-4-pregnene-3,20-dione;
 11 β ,21-dihydroxy-16 α -methyl-4-pregnene-3,20-dione;
 11 β ,21-dihydroxy-4-pregnene-3,20-dione;
 11 β ,21-dihydroxy-6 α -methyl-4-pregnene-3,20-dione;
 9 α -fluoro-11 β ,16 α ,17 α ,21-tetrahydroxy-4-pregnene-3,20-dione;
 9 α -fluoro-11 β ,16 α ,17 α ,21-tetrahydroxy-1,4-pregnadiene-3,20-dione;
 9 α -fluoro-11 β ,17 α ,21-trihydroxy-1,4-pregnadiene-3,20-dione;
 9 α -fluoro-17 α ,21-dihydroxy-4-pregnene-3,11,20-trione;
 9 α -fluoro-17 α ,21-dihydroxy-1,4-pregnadiene-3,11,20-trione;
 9 α -fluoro-11 β ,16 α ,17 α ,21-tetrahydroxy-2-methyl-1,4-pregnadiene-3,20-dione;
 9 α -fluoro-11 β ,16 α ,17 α ,21-tetrahydroxy-2 α -methyl-4-pregnene-3,20-dione;
 6 α ,9 α -difluoro-11 β ,17 α ,21-trihydroxy-4-pregnene-3,20-dione;
 6 α ,9 α -difluoro-11 β ,16 α ,17 α ,21-tetrahydroxy-4-pregnene-3,20-dione;
 6 α ,9 α -difluoro-11 β ,17 α ,21-trihydroxy-1,4-pregnadiene-3,20-dione;
 6 α ,9 α -difluoro-11 β ,16 α ,17 α ,21-tetrahydroxy-1,4-pregnadiene-3,20-dione;
 9 α -chloro-11 β ,16 α ,17 α ,21-tetrahydroxy-4-pregnene-3,20-dione;
 9 α -chloro-11 β ,17 α ,21-trihydroxy-4-pregnene-3,20-dione;
 9 α -fluoro-11 β ,16 α ,17 α ,21-tetrahydroxy-6 α -methyl-1,4-pregnadiene-3,20-dione;
 9 α -fluoro-11 β ,17 α ,21-dihydroxy-16 α ,17 α -isopropylidene-3,20-dione-

10 dioxo-4-pregnene-3,20-dione;
 9 α -fluoro-21-hydroxy-16 α ,17 α -isopropylidenedioxy-4-pregnene-3,11,20-trione;
 9 α -fluoro-16 α ,17 α -ethylidenedioxy-11 β ,21-dihydroxy-1,4-pregnadiene-3,20-dione;
 9 α -fluoro-11 β ,21-dihydroxy-16 α ,17 α -methoxymethylenedioxy-1,4-pregnadiene-3,20-dione and
 9 α -fluoro-16 α ,17 α -(1-ethoxy)ethylidenedioxy-11 β ,21-dihydroxy-1,4-pregnadiene-3,20-dione.

EXAMPLE 12

*Preparation of steroidal 21-oximes*15 Using the procedures of Examples 1, 3, 6, etc. for the selective formation of the 21-aldehyde oximes from the corresponding 20-keto-21-aldehydes, the 20-keto-aldehydes prepared as in Example 11 are converted to their 21-oximes as shown above wherein R is a steroid moiety attached at the 17-position.

EXAMPLE 13

*Preparation of steroidal amines*20 Using the procedure of Examples 2, 4, 7, etc. for the reduction of the 21-oximes of steroidal 20-keto-21-aldehydes, the 20-keto-21-aldehyde 21-oximes of Example 12 are reduced to the corresponding 21-aminosteroids. A wide variety of mineral acids are used for preparation of the aminosteroid salts such as hydrochloric acid, hydrobromic acid, sulfuric acid, nitric acid, perchloric acid, phosphoric acid, hydroiodic acid, hydrofluoric acid, phosphorous acid, chloroplatinic acid, etc.; and selected organic acids are also used for salt preparation such as oxalic acid, acetic acid, propionic acid, trichloracetic acid, dichloracetic acid, chloracetic acid, trifluoroacetic acid, difluoroacetic acid, picric acid, succinic acid, formic acid, methanesulfonic acid, ethanesulfonic acid, etc. As shown above R is a steroid moiety attached at the 17-position and A is a pharmaceutically accepted acid anion.

EXAMPLE 14

Preparation of 9 α -fluoro-11 β ,17 α -dihydroxy-21-propionylamino-4-pregnene-3,20-dione

25 50 Using the procedure of Example 2 for the preparation of 21-acetylaminosteroids except that in place of the acetic anhydride propionic anhydride is used the corresponding 21-propionyl-amino-steroid, 9 α -fluoro-11 β ,17 α -dihydroxy-21-propionylamino-4-pregnene-3,20-dione is obtained.

EXAMPLE 15

Preparation of 21-butyrylaminio-9 α -fluoro-11 β ,17 α -dihydroxy-4-pregnene-3,20-dione

55 60 Using the procedure of Example 2 for the preparation of the 21-acetylaminosteroid and replacing acetic anhydride with butyric anhydride, the corresponding 21-butyrylaminio derivative is formed which is 21-butyrylaminio-9 α -fluoro-11 β ,17 α -dihydroxy-4-pregnene-3,20-dione.

EXAMPLE 16

Preparation of 21-amino-9 α -fluoro-11 β -hydroxy-16 α ,17 α -isopropylidenedioxy-1,4-pregnadiene-3,20-dione hydrochloride

65 70 A solution of 1.0 g. of 9 α -fluoro-11 β -hydroxy-16 α ,17 α -isopropylidenedioxy-3,20-dioxo-1,4-pregnadien-21-al 21-oxime dissolved in 100 ml. of glacial acetic acid is treated with 2.0 g. of zinc dust, added over a period of 15 minutes at room temperature. The reaction mixture is stirred an additional 45 minutes, then filtered from insolubles. The

filtrate is evaporated to dryness under reduced pressure, the residue shaken with water, and the insolubles filtered off. The aqueous filtrate is diluted with an equal volume of methanol and this solution is passed through a column containing a strong anion exchange resin of the styrenedivinyl benzene type (which contains quaternary ammonium groups) (such as, for example, Dowex I) in the chloride form. The column is further washed with methanol containing 30% water until the amino steroid is completely removed from the resin. The amino steroid fraction is evaporated under diminished pressure to dryness, and the resulting residue is crystallized from methanol-diethyl ether, yielding crystalline 21-amino-9 α -fluoro-11 β -hydroxy-16 α ,17 α -isopropylidenedioxy-1,4-pregnadiene-3,20-dione hydrochloride.

We claim:

1. The compound 21-acetylamino-9 α -fluoro-11 β ,17 α -di-hydroxy-4-pregnene-3,20-dione.
2. The compound 21 - amino-9 α -fluoro-11 β -hydroxy-16 α ,17 α -isopropylidenedioxy-1,4-pregnadiene-3,20-dione.
3. The compound 21 - acetylamino-9 α -fluoro-11 β -hydroxy - 16 α ,17 α - isopropylidenedioxy - 1,4-pregnadiene-3,20-dione.
4. The compound 9 α - fluoro-11 β -hydroxy-16 α ,17 α -isopropylidenedioxy-3,20-dioxo-1,4-pregnadien-21-al.
5. The compound 9 α - fluoro-11 β ,17 α -dihydroxy-21-propionylamino-4-pregnene-3,20-dione.
6. The compound 21 - butyryl-amino-9 α -fluoro-11 β ,17 α -dihydroxy-4-pregnene-3,20-dione.
7. The compound 9 α - fluoro-11 β ,17 α -dihydroxy-3,20-dioxo-4-pregnene-21-al 21-oxime.
8. The compound 9 α -fluoro-11 β -hydroxy-16 α , 17 α -isopropylidenedioxy - 3,20 - dioxo-1,4-pregnadien-21-al 21-oxime.
9. The compound 9 α - fluoro-11 β ,17 α -dihydroxy-16 α -methyl-3,20-dioxo-1,4-pregnadiene-21-al 21-oxime.
10. A process for the production of a member selected from the group consisting of 21-amino and 21-acetylamino steroids of the pregnane series which comprises reaction of the corresponding 20,21-dicarbonyl steroid of the pregnane series with a member selected from the group consisting of hydroxylamine and hydroxylamine salts to produce the corresponding 21-oxime, and reacting the oxime with elemental zinc and a member selected from the group consisting of lower aliphatic carboxylic acids and lower aliphatic carboxylic acid-lower aliphatic carboxylic acid anhydride mixtures and recovering said compound therefrom.

11. A compound selected from the group consisting of:

wherein C_2C_1 is a divalent radical selected from the group consisting of CH_2CH_2 and $\text{CH}=\text{CH}$ radicals, X is selected from the group consisting of hydrogen, chlorine and fluorine atoms, Z is a divalent radical selected from the group consisting of

radicals, R¹ is selected from the group consisting of hydrogen and lower alkyl radicals, R² is selected from the group consisting of hydrogen, halogen and lower alkyl radicals, R³ is selected from the group consisting of hy-

drogen, hydroxyl, fluorine, lower alkyl and lower alkanoyloxy radicals, at least one of the radicals R² and R³ being other than hydrogen and lower alkyl, R⁴ is selected from the group consisting of hydrogen, hydroxyl and lower alkanoyloxy radicals and R³ and R⁴ when taken together form a member selected from the group consisting of lower alkylidenedioxy and (1-alkoxy)-lower alkylidenedioxy radicals and pharmaceutically acceptable acid addition salts.

10. 12. A compound of the formula:

25. wherein C_2C_1 is a divalent radical selected from the group consisting of CH_2CH_2 and $\text{CH}=\text{CH}$ radicals, X is selected from the group consisting of hydrogen, chlorine and fluorine atoms, Z is a divalent radical selected from the group consisting of

radicals, R¹ is selected from the group consisting of hydrogen and lower alkyl radicals, R² is selected from the group consisting of hydrogen, halogen and lower alkyl radicals, R³ is selected from the group consisting of hydrogen, hydroxyl, fluorine, lower alkyl and lower alkanoyloxy radicals, R⁴ is selected from the group consisting of hydrogen, hydroxyl and lower alkanoyloxy radicals and R³ and R⁴ when taken together form a member selected from the group consisting of lower alkylidenedioxy and (1-alkoxy)-lower alkylidenedioxy radicals and R⁵ is a lower alkanoylamino radical.

45. 13. A compound of the formula:

60. wherein C_2C_1 is a divalent radical selected from the group consisting of CH_2CH_2 and $\text{CH}=\text{CH}$ radicals, X is selected from the group consisting of hydrogen, chlorine and fluorine atoms, Z is a divalent radical selected from the group consisting of

radicals, R¹ is selected from the group consisting of hydrogen and lower alkyl radicals, R² is selected from the group consisting of hydrogen, halogen and lower alkyl radicals, R³ is selected from the group consisting of hydrogen, hydroxyl, fluorine, lower alkyl and lower alkanoyloxy radicals, R⁴ is selected from the group consisting of hydrogen, hydroxyl and lower alkanoyloxy radicals and R³ and R⁴ when taken together form a member

11

selected from the group consisting of lower alkylidene-dioxy and (1-alkoxy)-lower alkylidenedioxy radicals.

UNITED STATES PATENT OFFICE
CERTIFICATE OF CORRECTION

Patent No. 3,020,275

February 6, 1962

Michael Marx et al.

It is hereby certified that error appears in the above numbered patent requiring correction and that the said Letters Patent should read as corrected below.

Column 3, line 16, for "fo" read -- of --; column 5, lines 57 and 58, strike out the italicized heading "Preparation of 21-acetylamino-9 α -fluoro-11 β -hydroxy-16 α ,17 α -isopropylidene-dioxy-1,4-pregnadiene-3,20-dione" and insert instead -- Preparation of 9 α -fluoro-11 β ,17 α -dihydroxy-16 α -methyl-3,20-dioxo-1,4-pregnadiene-21-al 21-oxime --, in italics.

Signed and sealed this 19th day of June 1962.
